UNITED STATES PATENT OFFICE.

ALBERT EARL CRANSTON, OF SPOKANE, WASHINGTON.

BINDING MACHINE.

Application filed February 10, 1920. Serial No. 357,601.

To all whom it may concern:

Be it known that I, ALBERT E. CRANSTON, a citizen of the United States, and a resident of Spokane, in the county of Spokane and State of Washington, have invented certain new and useful Improvements in Binding Machines, of which the following is a specification.

My invention relates to binding machines generally and particularly to a machine for securing the parts comprised in a box, barrel or the like into shocks or bundles, and is a continuation of my application Serial No. 272,264, filed January 21, 1919. A purpose 10 of my invention is the provision of a binding machine which is capable of quickly and effectively binding bundles of material irrespective of their dimensions and without the necessity of the adjustment of any part of 15 the machine.

It is also a purpose of my invention to provide a binding machine which includes a knotted mechanism for tying the end of a loop of wire forming the subject-matter of 20 a separate application, a wire wrapping needle and an apparatus for feeding the bundles to the knotted the operation of these elements being entirely automatic and controlled manually by the depression of a lever 25 or automatically by the placing of material on the table of the machine, this arbitrary control being rendered inactive to cause the entire machine to come to rest after the tying of a bundle.

30 I will describe one form of binding machine embodying my invention and will then point out the novel features thereof in claims.

In the accompanying drawings:—

40 Figure 1 is a side elevation of the machine showing position of mechanism just after the completion of the bundling operation;

45 Figure 2 is a side elevation of the machine from the opposite side of Figure 1 but showing a stack of loose shocks just placed on the machine bed ready for bundling;

50 Figure 3 is a view similar to Figure 2 but showing the position of the various parts of the machine as the material is being advanced towards the binding wire; in dotted

lines is shown the position the material and wire will assume when the material has been advanced to its limit;

Figure 4 is a view similar to Figure 1 but 55 showing the position the various parts will assume while the knotting action is taking place;

Figure 5 is a section on line 5—5 of Figure 60 1;

Figure 6 is a section on line 6—6 of Figure 5;

Figure 7 is a section on line 7—7 of Figure 5;

Figure 8 is a longitudinal sectional view, 65 showing the connection between the rack mechanism and the carriage; and the method of automatically continuing the operation of the machine during the complete bundling and knotting of a single stack of 70 material;

Figure 9 is a section on line 9—9 of Figure 8;

Figure 10 is a section on line 10—10 of Figure 8; 75

Figure 11 is a section on line 11—11 of Figure 8;

Figure 12 is a section on line 12—12 of Figure 8;

Figure 13 is a sectional view, showing the 80 push fingers during the retraction of the carriage; and

Figure 14 is an enlarged detail view of the friction clutch for holding the tying wire taut. 85

In the drawings, wherein is illustrated the preferred form of the invention as now in actual use, two wire reels as 1 and 2 are illustrated so that with the machine, a bundle as B, of shingles, box shocks, or other similar articles, may have two loops of wire wrapped and fastened around the bundle, or a single bundle may be wrapped with a single loop, or two bundles may be wrapped with a single loop simultaneously as will be 95 hereinafter more readily understood. The wire reels are supported in brackets 3 on the axle 4, and the brackets are fixed above the table top 5, supported above the floor by the corner legs 6, etc. and the shingles that are to be made into a bundle are placed on the top of the table and moved or pushed from right 100

to left in Figure 1, and in the reverse direction, from left to right, in Figure 2.

The shingles are moved to position to be wrapped by pressure from a pair of push fingers 7 and 8 that travel longitudinally of the table top through the slots 9 therein and are pivoted at 7' and 8' on the side plates 10, 10' of a carriage that reciprocates beneath the table top and includes slide bearings 11 to move over the four guide bars 12, arranged in pairs at each side of the longitudinal center of the table beneath the top, and a transverse brace or rod 12' joins the side plates. The four guide bars are supported in brackets 13 and 13' depending from the under side of the table, and the carriage is reciprocated through the action of a pitman 14, or a pair of pitmen 14, that are pivotally connected at 15 to the cross bar 16 extending between the two side plates of the carriage. When the push fingers are in operative position they stand upright above the table top and pass from right to left in Figure 1, through the slots 9, but upon the return stroke of the carriage or cross-head that carries the push fingers, the latter are turned down beneath the table top in order that additional shingles may be placed in position on the table during the return stroke of the cross-head, thus saving the time that would otherwise be wasted if the operator were required to wait until the upright push finger returned to operative or initial position.

In Figures 4, 8, 11 and 13 the means for turning the fingers to upright position is illustrated as studs 17 projecting transversely into the two slots 9, 9 through which the fingers pass as they are reciprocated, and each finger having a cam edge *a* which rides over the corresponding stud 17 and is thereby swung on its pivot 7' or 8' as in dotted lines Figure 13 to upright position. After being elevated, the finger is held in upright position by a latch bar 19 that is slidable in slots 20 in the side plates of the carriage, and adapted to slide under the end 21 of the finger and hold it locked in upright position. The latch bar 19 is moved as the carriage reaches the end of its return movement by engagement with an abutment or stop 22 against which the latch impinges and additional movement of the carriage is permitted to slide the latch under the finger 7 or 8 by notching the finger at 23 to accommodate the elevating stud 17. Upon the working stroke of the carriage, the fingers are held upright by the latch bar 19 under the ends 21, and when the end of the working stroke is reached the latch bar encounters another stop or abutment 24 (Figure 8) and is moved out from under the fingers so that they may fall by gravity to retracted position and thus be returned to the front of the machine to be again elevated.

As the unpacked shingles X are fed forward by the push fingers they are shoved against the two wires 25 and 26 that are unwound from the reels 1 and 2, respectively, and the wires are fed to proper position for engagement by the shingles through the instrumentality of angular needles or L-shaped arms 27 and 27' that are pivoted above the table by being secured to a rock shaft 28 which is journaled in the frame or bracket 3, 75 and needles 27 and 27' are designed to pass vertically through slots or openings 29 in the table top. A pair of guide rollers 30 and 31 for the wires are provided on the needles 27 and 27'. Inasmuch as each of 80 these wire feed arms or needles 27 and 27' are alike, a description of one and its connections will suffice for both. The angular arm is swung on its pivot by mechanism to be described, and as its free end swings through the slot 29 it carries with it a length of wire sufficient to form a loop about the bundle and then this loop is knotted by twisting the ends together as described and claimed in a separate application for patent. 85 The wire is pulled from the reel on the down stroke of the feed arm, and this down stroke is accomplished by means of a short cam member 32, and the upstroke of the arm is accomplished by a longer cam member 33, 90 on the main shaft 34 which is journaled beneath the table in a frame portion integral with the supporting legs of the table. Cam 32 is secured to cam 33 by bolts *b*. In Figures 2, 3 and 4 the operation of the cams is 100 clearly shown, and their connections with the rock shaft or pivot 28 for the two feed arms will be readily understood, as it is evident that with the cam member and shaft turning in the direction of the arrow, when 105 the front end 33' of the cam 33 contacts with the pawl 35 pivoted to the frame at 36 and connected by link 37 to the crank arm 38, the shaft 28 will be rocked and the free end of the feed arm will be swung upwardly 110 from the slot 29 in the table, the rollers 30 and 31 passing over the wire, which at this time remains stationary, since its extremity is held tightly within the knotter K, and the feed arm is held out of the way of the 115 bundle B as the twisting of the ends of the wire is being completed, and also of the incoming package X that is to be wrapped. 120 The feed arm is positively swung downward by the cam member 32 in engagement with a lever arm 39, rigid on the rock shaft 28, and as the cam members revolve continuously during one complete bundling and knotting action, they alternately lower and elevate the feed arm to pull the wire down through the table top on the down stroke to be looped about the bundles of shingles. To assist in preventing the wire from unreeeling too freely, and to hold the wire under suitable tension while the bundle is 125 130

being pushed against the vertical wire to form the loop, a wire tensioning device is provided to engage the wire as it unreels, with sufficient pressure as to permit its passage, but at the same time hold it taut. The tension device comprises a pair of disks 40 and 41, best shown in Figure 14, as loose upon the shaft 42 which is supported or fixed in the brackets 43, 44 that are adjustable toward or away from each other by the two set screws 45 and the bolt 46. Bracket 43 is secured to a cross bar *c* (Figure 5). Between the disk 41 and the bracket 44 is interposed a coiled spring 47 surrounding the shaft 42, and the disk 40 has a central boss or extension 48 that projects into the recess or seat 49 of the disk 41 so that these two disks may be kept alined but may move laterally with relation to one another. The disks are designed to grasp or frictionally engage the wire as it passes between them, and for this purpose a forked lever 50 projects between the flat face of disk 40 and the bracket 43 and over the shaft 42, the other end of the lever being pivoted at 51 to a lever arm 52^a on the rock shaft 28. Now, when the feed arm is swung downwardly, the lever arm 51 will shove or push the forked lever 50 forward, and as the bifurcated end of this forked lever is wedge-shaped, as at 50' it is apparent that the disks will be pushed laterally against the spring 47 and will be pushed together to clasp the wire as it passes therethrough and engage the wire with sufficient friction to retard its movement and make the wire taut so that the bundle may be pushed through it to form a loop.

By means of a knotting device the wire is cut and the two ends are then twisted together to secure the loop about the bundle, and there are two of these devices, one a stationary device indicated at 52 and the other an adjustable device indicated at 53, The adjustable device is movable in a slot 54 in the table top and may be moved toward or away from the stationary device by means of the hand wheel 55, so that the wires may be spaced, within limits, as desired on the bundle, and the knotting devices include operating, vertically arranged shafts 56 and 56'.

The feeding device for the shingles, the wire feed mechanism and the knotting device are all actuated from the same source of power transmitted through the power wheel 57 and power shaft 58, the latter supported or journaled in movable bearings 59, and movable through the foot lever 60 pivoted at 61 (Figure 6) in the frame of the machine. The power shaft has thereon a small friction pulley 62 which engages a larger friction pulley 63 on the counter shaft 64 that is journaled in bearings 65 at the rear of the machine, and it is apparent that down-

ward pressure on the free end of the lever or pedal 60 will lift the wheel 62 into engagement with the wheel 63 to revolve the counter shaft 64, from which latter shaft, connections are distributed to the devices for performing the different steps in the wrapping of the bundle.

Friction wheel 62 is normally held out of frictional engagement with wheel 63 by means of the spring *d* which extends from the free end of lever 60 to the under side of table top 5, consequently maintaining the free end of lever 60 in a relatively raised position and the end of lever 60 which is on the opposite side of fulcrum point 61 in a relatively depressed position. In order to cause the machine to continue in operation during the bundling action without the operator continuing pedal pressure on lever 60 and to cause the machine to automatically stop when the bundling and knotting actions are complete, I have provided the following: Pivoted to lever 60 at *e* is the upright rod *f* which is loosely supported in an upright position by strap *g*. On the upper extremity of rod *f* is provided the roller *h* which lies in the path of the depressing member *i* (Figures 8, 11 and 12). Member *i* is secured to carriage slide member 10' at *j* and is supported beneath the top 5 by means of strap *k*. The free extremity of member *i* is provided with the cam face *m* for a purpose to be hereinafter described.

Counter shaft 64 carries a small toothed pinion 66 which meshes with the large gear wheel 67 on the main shaft 34 so that the latter shaft will be continuously revolved as long as counter-shaft 64 is revolved.

The reciprocating movement is imparted to the carriage by the following means,— (see Figures 8, 9, 10). A rack shaft 74 is supported beneath the table top 5 by means of hangers *n* and carries the sprocket 73 which is connected to sprocket 71 on shaft 64 by means of chain 72 (Figure 6). Rack wheels 75 are positioned near the opposite extremities of rack shaft 74. Rack members, generally indicated at *p* are attached to pitmen 14 at *q* and are constructed as follows; (description is of one, only, since they are exactly alike) *p* is recessed as at *r* and provided with the internal rack teeth 76 extending continuously around the perimeter of the recess. A countersunk recess *s* follows the same contour as recess *r* and provides a runway for the ends *t* of the shaft 74 which ends project into said recess *s*. It will be seen that since shaft 74 and wheels 75 are fixed with respect to the top 5 and since the travel of *p* is forced and fixed through the engagement of *t* and *s*, that the revolving of wheels 75 will cause member *p* to travel around said wheels by the alternate engagement of the opposed teeth of the rack 130

member and will thereby reciprocate the carriage through the pitmen 14. This travel is indicated by the various positions in full and dotted lines of member *p* in Figures 5 2, 3 and 4.

The wire feed arms or needles 27 and 27' are oscillated through the instrumentality of cams 32 and 33 as before described, by reason of their being fixed to main shaft 34.

10 The two knotters or knotting devices 52 and 53 are operated through their vertical shafts 56 and 56' which have at their lower extremities the bevel gears 77 and 77', these being engaged by bevel gears 78 and 78' on 15 the knotter shaft 79. To maintain a driving connection between the gear 78' and the shaft 79 during any adjustment of the knotter 53 the gear 78' is keyed to the shaft so as to slide thereon and at the same time 20 rotate with the same. Knotter shaft 79 is journaled in the members 79' depending from the machine frame. The knotter shaft 79 carries sprocket 80 and is operated by a chain 81 which is trained over sprocket 80 25 and also over sprocket 82, the latter being fixed on shaft 70. Shaft 70 is supported by hangers *u* and carries a pinion 69 which will be intermittently engaged by the segment 68 which is secured to the spokes of gear 67. 30 While the operation of the machine may be initiated through the friction drive by pressure from the foot on the lever 60, it may be, in addition, initiated mechanically through the instrumentality of an actuating 35 lever 83 pivoted at 84 to the table top and connected by a link 85 to the lever 60, whereby when material to be bundled is placed on the lever 83, the lever 60 will be depressed and frictional engagement between wheels 40 62 and 63 be initiated.

I will now describe the operation of the machine. Referring first to Figure 1, I have shown the position of the various parts just after bundle B has been bound and it will 45 be noted that lever 60 and 83 are raised, the machine being at rest. Upon material X being placed on the table top as in Figure 2, the lever 83 is depressed thereby as shown, thereby causing frictional engagement between 50 wheels 62 and 63. The friction drive will immediately cause wheels 75 to be revolved through sprocket wheels 71, 73 and the chain 72 thereby causing rack member *p* and consequently carriages 10 and 10' and 55 fingers 7 and 8 to move forward as shown in Figure 3. Since member *i* will be carried forward by the carriage, the cam surface *m* will ride over roller *h* and the under surface of *i* will then continue to contact with said 60 roller and hold the rod *f* and hence lever 60 depressed during one forward and backward reciprocation of the carriage, during which reciprocation one bundle is completely bound. At the completion of one reciprocation spring *d* will raise lever 60 and stop 65

the machine, member *i* then being back in the position of Figure 8.

Practically simultaneously with the forward movement of the carriage, cam 33 will contact with lever 35 and raise needles 27 70 and 27', leaving a stretch *w* of wire exposed in the path of bundle X (Figure 3). As fingers 7 and 8 push bundle X to their limit of travel (dotted line, Figure 3) the wire 75 will be withdrawn from the reels and will position itself around three sides of the bundle. As fingers 7 and 8 drop and are retracted by the reciprocating motion of the carriage, cam 32 will contact with rod 39 and cause the needles 27 and 27' to lower, and 80 will hold them lowered to the end of the cycle. This lowering of the needles complete the wrap around the bundle (Figure 4).

When needle 27 is well down, segment 68 85 will engage pinion 69 and, through the mechanism described, actuate the knotters 52 and 53 and twist the severed ends of the wire together.

From the foregoing description, taken in conjunction with the accompanying drawings, it will be manifest that I have provided a binding machine which when initially started by the depression of the lever 60 either manually or through the placing of the material on the table, feeds the material to the knotters, actuates the needles to effect a wrapping of the material by the tying wires, and subsequently actuates the knotters to effect a tying of the material into a 90 bundle.

100 By virtue of the arrangement of the feeding mechanism with respect to the knotters, it is obvious that a bundle of any dimensions (within certain limits) can be effectively tied without the necessity of adjusting any part of the machine. It will be further noted that because of the adjustability of one of the knotters the tying of the bundle by such knotter can be effected at various points within the length of the bundle to thereby effectively secure material of various configurations and dimensions.

110 Although I have herein shown and described only one form of binding machine embodying my invention, it is to be understood that various changes and modifications may be made herein without departing from the spirit of the invention and the spirit and scope of the appended claims.

115 Having thus described my invention, what I claim is:—

1. A binding machine comprising a table, a knotter supported in the table, a reciprocating carriage arranged below the table, fingers carried by said carriage, said fingers being movable through said table and capable of occupying one extreme position wherein they project above the table and another extreme position in which they are disposed below the table, means for recipro- 120

- eating said carriage, and means operable by the movement of said carriage for causing said fingers to occupy one extreme position or the other according as the carriage is 5 moved in one direction or the other.
2. A binding machine comprising a table, a knotter supported in the table, a reciprocating carriage arranged below the table, fingers carried by said carriage, said fingers 10 being movable through said table and capable of occupying one extreme position wherein they project above the table and another extreme position in which they are disposed below the table, means for reciprocating said carriage, and means operable by the movement of said carriage for causing said fingers to project above the table when the carriage is moving in one direction and for causing the same to be disposed below 15 the surface of the table when the carriage is moved in the other direction.
3. The combination with a feeding table and reciprocating carriage, of cam operated pivoted fingers on the carriage and an abutment 20 on the table therefor, a slideable latch bar on the carriage to hold the fingers in operative position, and means for moving the latch bar to latched position.
4. The combination with a feeding table 25 and reciprocating carriage, of cam operated pivoted fingers on the carriage, and an abutment on the table therefor, a slideable latch bar on the carriage to hold the fingers in operative position, means for moving the latch bar to latched position in one extreme 30 position of the carriage, and means for moving the latch bar to releasing position when the carriage is in the other extreme position.
5. A binding machine comprising, a knotter, mechanism for feeding articles to the knotter, a needle, a wire supply having the wire trained over said needle, a normally inactive tensioning device interposed between said supply and needle and adapted 45 to hold the wire under tension, and means operable by said needle for actuating said device to grip said wire.
6. A binding machine comprising, a knotter, mechanism for feeding articles to the knotter, a needle movable to occupy an elevated position and a lowered position with 50 respect to said knotter, a wire supply for the wire trained over said needle, a normally inactive tensioning device interposed between said supply and needle and adapted to hold the wire under tension, and means operable when said needle moves to its lowered 55 position for actuating said device to grip the wire.
7. A binding machine comprising a knotter, a carriage for feeding a bundle to the knotter, a needle for supporting and manipulating the wire to cause the same to encompass the bundle, means for actuating for predetermined periods said carriage, said 60 needle and said knotter in the order mentioned, and means for controlling said means, comprising, a driving shaft, a driven shaft, a lever connected to the driving shaft and capable of occupying one extreme position 70 wherein said shafts are operatively connected and a second extreme position in which said shafts are disconnected, means for biasing the lever to the second extreme position, and means operable by said carriage for maintaining the lever in the other extreme position for a predetermined period after the lever has been initially moved thereto.
8. A binding machine comprising a knotter, a carriage for feeding a bundle to the knotter, a needle for supporting and manipulating the wire to cause the same to encompass the bundle, means for actuating for predetermined periods said carriage, said 75 needle and said knotter in the order mentioned, means for controlling said means comprising, a driving shaft, a driven shaft, a lever connected to the driving shaft and capable of occupying one extreme position 80 wherein said shafts are operatively connected and a second extreme position in which said shafts are disconnected, means for biasing the lever to the second extreme position, and means operable by said carriage for maintaining the lever in the other extreme position for a predetermined period after the lever has been initially moved thereto.
9. A binding machine comprising a feeding carriage, a wire manipulating needle, a knotter, and mechanism for actuating all of said elements for predetermined periods and in the sequence mentioned comprising, a driven shaft and a driving shaft movable 90 to engage or disengage the driven shaft, and means operable by movement of the feeding carriage for maintaining the driving shaft in engagement with the driven shaft for a predetermined period.
10. A binding machine comprising a table, a carriage slideable beneath the table, means for reciprocating said carriage comprising, continuous rack members connected to the carriage, gears meshing with said members, and means for rotating said gears.
11. A binding machine comprising a table, a knotter supported on the table, a reciprocating carriage arranged below the bed of the table, fingers mounted on and bodily movable with the carriage, said fingers being movable through said table and capable of occupying one extreme position wherein they project above the bed of the table to engage the material on the table and deliver the same to the knotter and another extreme position in which they are disposed below the bed of the table so as to be in disengaging position with respect to the material on the table, means for reciprocating said 120 carriage for predetermined periods.
12. A binding machine comprising a table, a knotter supported on the table, a reciprocating carriage arranged below the bed of the table, fingers mounted on and bodily movable with the carriage, said fingers being movable through said table and capable of occupying one extreme position wherein they project above the bed of the table to engage the material on the table and deliver the same to the knotter and another extreme position in which they are disposed below the bed of the table so as to be in disengaging position with respect to the material on the table, means for reciprocating said 125 carriage for predetermined periods.
13. A binding machine comprising a table, a knotter supported on the table, a reciprocating carriage arranged below the bed of the table, fingers mounted on and bodily movable with the carriage, said fingers being movable through said table and capable of occupying one extreme position wherein they project above the bed of the table to engage the material on the table and deliver the same to the knotter and another extreme position in which they are disposed below the bed of the table so as to be in disengaging position with respect to the material on the table, means for reciprocating said 130 carriage for predetermined periods.

carriage, and means operable by the movement of said carriage for causing said fingers to project above the table when moved in the direction of the knotter and for causing the same to be disposed below the table when moved away from the knotter whereby after a given bundle of material has been

started toward the knotter, a second bundle of material may be immediately placed on the bed of the table in position to be engaged 10 by the next movement of the carriage in the direction of the knotter.

ALBERT EARL CRANSTON.
